UNITED STATES PATENT OFFICE.

GEORGE ULSOMER, OF HAUBSTADT, INDIANA.

CAR-COUPING.

SPECIFICATION forming part of Letters Patent No. 297,877, dated April 29, 1884.

Application filed March 11, 1884. (No model.)

To all whom it may concern:

Be it known that I, GEORGE ULSOMER, a citizen of the United States, residing at Haubstadt, in the county of Gibson and State of Indiana, have invented certain new and useful Improvements in Car-Couplers, of which the following is a full, clear, and exact description, reference being had to the accompanying drawings, forming part of this specification,

10 in which—

Figure 1 is a perspective view of a draw-head with my improvements attached. Fig. 2 is a cross-sectional view of the same on the line $\alpha\alpha$ of Fig. 1; Fig. 3, a detail to be referred to.

15 My invention relates to automatic car-couplings; and it consists in the novel construction, arrangement, and combination of devices, as will be hereinafter more fully set forth and specifically claimed.

20 To enable others skilled in the art to make and use my invention, I will proceed to describe the exact manner in which I have carried it out.

Referring to the drawings, in which similar 25 letters of reference indicate corresponding parts, A represents a draw-head constructed in the usual manner, and having the usual perforation, a, adapted to receive the coupling-pin.

30 In one side of the draw-head is formed an opening, b, through which is passed a slotted arm, B, secured to a metal plate, a', located within the draw-head. A flat spring, B', is rigidly attached to the slotted arm B, and has

35 its other end secured to the side of the draw-head. A vertical rod, C, is secured to the body of the car at a point, c, by an eyebolt or other well-known means, and a shoulder or annular ring is adapted to strike against the

40 eye of the bolt when the rod C is drawn upward for a purpose hereinafter described. The vertical rod C has formed near its lower end an angular projection, C', which extends over the draw-head, while the portion c' of 45 this angular projection constitutes the coupling-pin, which is held over the draw-head and on a line with the perforation formed in said draw-head.

In the extreme lower end of the vertical rod 50 C is formed a depression, d, which engages the

slotted arm B when the coupling-pin is raised and in position ready for coupling with the link of the approaching car, as shown in Fig. 1.

In order to more fully illustrate my invention, I have shown in the drawings another 55 draw-head, representing it attached to an approaching car. This draw-head is constructed in the usual manner, except on the side of the same, I have secured a plate, D, having an eye or loop, e, and a vertical groove, e', formed 60 on its front face; or, if desired, the loop and groove can be cast or otherwise made to form an integral part of the draw-head. In this loop and groove rests the lower end of a vertical rod, E, constructed substantially like the 65 rod C, while an enlarged portion, f, formed on this rod E, is adapted to engage with or rest upon the loop e when the vertical rod E is not in use. The lower end of the rod E, after passing through the loop, is curved up- 70 and at right angles to the upper portion 75 of the rod, and is so constructed that the portion g will lie beneath the coupling-link. The portion g may be notched, so as to secure a more positive action on the coupling-link. Thus it will be seen that by simply drawing up the rod E the coupling-link G may be adjusted so as to readily enter the draw-head of another car.

If desirable, I can attach the vertical rods 80 C and E to the same draw-head, and on opposite sides of the same; but I prefer to use them independently of each other, or on separate cars, as specified above.

The operation of my improved coupler is as 85 follows: The vertical rod E being in the position shown in the drawings, and the coupling-link G thereby adjusted, the car having the draw-head A' is caused to approach the draw-head A, when the coupling-link, on being passed 90 into the said draw-head A, comes in contact with the metal plate B', carrying the slotted arm B, and forces the said plate and arm outward, thereby releasing the vertical rod C from its contact with the slotted arm, and allowing the vertical rod to drop, and causing the coupling-pin to fall into the perforation formed in the draw-head A, thus securely coupling the cars together.

To uncouple the cars, the operator has sim- 100

ply to pull up the rod *c*, which carries the coupling-pin, when the link is immediately released.

Having thus described my invention, what I claim as new, and desire to secure by Letters Patent, is—

1. In an automatic car-coupler, the vertical rod *C*, having a coupling-pin, *c*, and a depression adapted to engage the slotted arm *B*, in combination with the draw-head *A* and a spring, *B'*, substantially as and for the purpose set forth.

2. In a car-coupling, the vertical rod *E*, having an enlarged portion, *f*, and a curved end *g*, adapted to adjust a coupling-link, in combination with a draw-head having an eye, *e*,

and groove *e'*, substantially as and for the purpose set forth.

3. The draw-head *A*, having the perforations *a* and *b*, in combination with the slotted arm *B*, metal plate *a'*, and a spring, *B'*, substantially as and for the purpose set forth. 20

4. In a car-coupling, the combination of the draw-heads *A A'*, vertical rods *C* and *E*, constructed substantially as shown, the coupling-link *G*, the slotted arm *B*, metal plate *a'*, and a spring, *B'*, all constructed to operate substantially as and for the purpose set forth. 25

GEORGE ULSOMER.
